UNITED STATES PATENT OFFICE

157,328

POURING CAP FOR A MILK BOTTLE

Johanna Beseke, Minneapolis, Minn.

Application December 21, 1948, Serial No. 150,292

Term of patent 3½ years

(Cl. D58—26)

To all whom it may concern:

Be it known that I, Johanna Beseke, a citizen of the United States, residing at 1701 West Lake Street, Minneapolis, in the county of Hennepin and State of Minnesota, have invented a new, original, and ornamental Design for a Pouring Cap for a Milk Bottle, of which the following is a specification, reference being had to the accompanying drawing, forming part thereof.

Fig. 1 is a top plan view of a pouring cap for a milk bottle, showing my new design;

Fig. 2 is a view in side elevation;

Fig. 3 is a view in rear elevation.

I claim:

The ornamental design for a pouring cap for a milk bottle, as shown.

JOHANNA BESEKE.
